No. 1722

Elihu J. Key, of Lowell Mass.
Assignor to
The Lowell Manufacturing Company
Letters Patent No 1722, dated March 3, 1863.

The schedule referred to in these Letters Patent and making part of the same

Dec. 1722

To all whom it may concern.

Be it known, that J. Clemir J. Key, of Lowell, in the County of Middlesex and State of Massachusetts, now temporarily residing in New York, have originated and designed a new pattern for carpets or other fabrics, of which the following is a full, clear and exact description, reference being had to the accompanying drawings, making part of this specification.

Fig A. is a rosette from which radiate small branches or sprigs, resting on the ground, 1. which is enclosed by the frame
2. B. is a small star surrounded by the wreath. 3. C. is an eight pointed, oblong block resting on the ground 4. which is enclosed by a frame supporting the vine 5. 5.

E and E', when matched, form a rectangular ground supporting a group of scrolls, and enclosed by the figured frame 6. 6.

7 and 8. are squares, covered with a diamond net work, and enclosed by figured frames.

Portions of the wreath or vine 5. 5. and the corner figures of the frame 6. 6. over lap the squares. 7 and 8.
9 and 10. are squares similar to 7 and 8. 11 and 12. are similar to E and E', respectively.

The colors employed for the different portions of the design, may be varied to suit the taste and wish of the manufacturer.

Claim

What I claim as my invention and desire to secure by letters patent,
